(57) **CLAIM**

The ornamental design for a display screen with graphical user interface, as shown and described.

DESCRIPTION

FIG. 1 is a front view of a display screen with graphical user interface showing our new design; and, FIG. 2 shows the display screen of FIG. 1 on a device. The broken line showing of the seven squares and rectangle and the icons in FIGS. 1-2, and of the remainder of a device containing the display screen in FIG. 2, is for environmental purposes only and forms no part of the claimed design.
